UNITED STATES PATENT OFFICE.

JEAN MARIE HEINRICH, OF PARIS, FRANCE, ASSIGNOR TO SOCIÉTÉ DES MOTEURS SALMSON (SYSTÈME CANTON-UNNÉ), OF PARIS, FRANCE.

AIR-COOLED-ENGINE CYLINDER.

Application filed November 25, 1924, Serial No. 752,220, and in France January 4, 1924.

The present invention has for its object an improved air-cooled cylinder for internal combustion engines.

According to the invention, the engine cylinder comprises a jacket which is made of a light and good heat-conducting metal and is provided with air cooling ribs, said jacket being separately secured to or preferably cast upon the cylinder properly so called. The jacket may be connected to the latter by all suitable mechanical means, and one important feature of the invention is that it can be used with cylinders which have already been constructed in view of other methods of cooling.

Other features of the invention will be set forth in the following description with reference to the appended drawings which are given by way of example and wherein:

20 Fig. 1 is a vertical section on the line C—C (Fig. 2) of an air-cooled cylinder for internal combustion engines, according to the invention.

Fig. 2 is a corresponding plan view.

25 Fig. 3 is a half section of the explosion chamber of the cylinder, on the line A—B of Fig. 2, and

Fig. 4 is a half section of the said chamber on the line B—C of Fig. 2.

30 Figs. 3 and 4 show modifications of the means connecting the cylinder and the jacket.

1 is the cylinder properly so called which is made of a strong metal, such as steel or 35 cast iron, and worked in the usual manner, said cylinder comprising (preferably integral with the cylindrical body 2) the cylinder head 3, the inlets 4 and outlets 5 with their respective valve seatings 6 and 7 and 40 valve guides 8 and 9, the ignition aperture 10 or the aperture 11 for compression cock, and the bearing parts 12 for securing the valve levers, and like parts.

The cylinder head and the major part 45 of the cylindrical body 2 are surrounded by a radiating jacket 13 which is made of a metal which is good conductor of heat and is preferably of a light nature, particularly for the cylinders of aeroplane engines; the 50 said metal may be for instance an alloy of aluminum. The jacket 13 is formed with cooling ribs 14 which are of suitable size and shape to offer a large surface of contact with the current of cooling air and an efficient 55 radiation of heat.

The said jacket 13 may consist of a number of pieces which are mechanically fitted upon the cylinder 1, but the drawings show a jacket which is cast around the said cylinder, the casting operation being performed 60 with greater facility than the adjustment of a jacket made in several parts, and the casting also affords a better adhesion of the metal of the jacket to the metal of the cylinder, so that the heat produced in the 65 cylinder is conducted to the exterior in a more effective manner.

Since the said jacket consists of a metal having relatively but little strength, it is not adapted to withstand heavy mechanical 70 stresses for any length of time, its function being limited in principle to the radiation of the heat. Means must therefore be provided to secure the proper connection between the said jacket and cylinder 1, at the 75 same time affording a good contact between the metals for the transmission of heat. When the said jacket is to be cast upon the cylinder, as herein represented, grooves 15 may be provided upon the cylinder body 2, 80 before casting, said grooves being longitudinal, helical or simply circular; said grooves are also shallow in order that the strength of the cylinder 1 shall not be diminished, but they may have a close spacing without 85 inconvenience. Suitable rings 16 of strong metal are preferably imbedded in the cooling ribs during the casting in order to secure a tight fitting upon the cylinder and to provide for a good maintenance for the jacket. 90 Should the wall of the cylinder 1 have a sufficient thickness, one may turn therein suitable bosses, such as the knob 17 which is formed on the cylinder head 3, in order to hold the metals together. On the thinner 95 parts of the cylinder wall separately secured knobs 18, screwed or riveted to the said wall, may be provided and serve the same purpose as the knobs 17.

Fig. 3 shows another method of connecting the said cylinder and jacket. When the jacket has been cast upon the cylinder, holes are formed through the double wall thus obtained and rivets 19 are inserted through said holes and are countersunk upon the inner surface of the cylinder. The said rivets may be made of a good conducting metal, and they will be more effective in withdrawing heat at the points on the cylinder at which they are situated. Should the metal 110

- of the said jacket, even though comparatively weak, be sufficiently malleable (which condition may be readily obtained) holes may be made, before the casting operation, in the wall of the cylinder, so that the metal of the jacket will form the nibs 20, Fig. 4, these being pounded down upon the interior of the cylinder after the manner of rivets 19 in order to secure a tight fit. The rivets 19 and the nibs 20 will constitute auxiliary heat-withdrawing means, these being disposed to advantage at the hottest points on the cylinder.
- The said jacket, whether applied in separate parts or cast in one piece, may be placed upon an already constructed cylinder which has been preliminarily designed for use with a water jacket, and in such case it is simply necessary to remove the said jacket and (in the case of a cast jacket) to take the necessary dispositions for obtaining suitable connecting means between the metals of the cylinder and the jacket 13. The slight addition in the mechanical strength which is afforded by the said jacket allows of forming grooves, rivet, holes, tappet holes, connecting knobs, or the like, upon the cylinder itself without diminishing the total strength of the cylinder. For cylinders arranged and machine-treated for use with a water jacket, the flange 21 which serves to secure the water jacket and is integral with the cylinder (Fig. 1) will constitute an additional element by which the lower part of the jacket 13 is connected to the cylinder.
- But for a specially-designed type of cylinder which is to be employed with the jacket according to the invention, the ar-

rangement will be facilitated inasmuch as the draftsman will now have the choice of all suitable dispositions for the above-mentioned connecting means.

Obviously, the said invention is not limited to the forms of construction hereinbefore described and illustrated, these being given solely by way of example, and in particular, all suitable means of connection between the cylinder properly so called and the radiating jacket may be employed without departing from the spirit of the invention.

Having now described my invention, what I claim as new and desire to secure by Letters Patent is:

1. An engine cylinder comprising in combination a cylinder core, an outer coating of a good heat-conducting metal cast upon said cylinder core and rivets for connecting said cylinder core to said coating.
2. An engine cylinder comprising in combination a cylinder core, an outer coating of a good heat-conducting metal cast upon said cylinder core and rivets for connecting said cylinder core to said coating and being also of a good heat conducting metal, and disposed at the points of the cylinder which are at the highest temperatures when the engine is working.
3. An engine cylinder comprising in combination a cylinder core, an outer coating of a good heat-conducting metal cast upon said cylinder core and flush rivets for connecting said cylinder core to said coating.

In testimony whereof I have signed my name to this specification.

JEAN MARIE HEINRICH.
